OIL CIRCUIT INTERRUPTER

Robert E. Friedrich, Pittsburgh, Pa., assignor to
Westinghouse Electric Corporation, East Pitts-
burgh, Pa., a corporation of Pennsylvania

Application September 27, 1947, Serial No. 776,569

6 Claims. (Cl. 200—150)

1

This invention relates to circuit interrupters in general, and more particularly, to arc-extinguishing structures and operating mechanisms therefor.

A general object of my invention is to provide an improved circuit interrupter in which an improved hydraulic operating mechanism is provided to effect operation of the contact structure.

Another object is to provide an improved arc-extinguishing unit in which the contact structure is hydraulically operated and which is provided with venting means to vent the unit following circuit interruption, which venting means is actuated by the improved hydraulic operating mechanism.

Still another object is to provide an improved circuit interrupter of the type establishing both a pressure-generating arc and an interrupting arc with fluid passage means interconnecting the two arcs. In my invention, I provide a separate fluid moving means to assist in low current interruption and I provide a separate passage interconnecting the fluid moving means with the interrupting arc to prevent contamination of the fluid sent by the fluid moving means toward the interrupting arc.

A further object is to provide an improved arc-extinguishing unit with venting means at opposite ends thereof to provide a chimney venting effect, and to provide hydraulic means which not only effects separation of the contact structure associated with the unit but also effects opening of the venting means following interruption of the circuit.

Another object is to provide an improved hydraulic operating mechanism for the contact means of a circuit interrupter in which the construction is such as to minimize hydraulic friction losses.

Still a further object is to provide an improved circuit interrupter of the type specified in the immediately preceding paragraph in which a separate delayed acting low current piston is incorporated which is actuated following a predetermined opening movement of the hydraulic operating mechanism.

Further objects and advantages will readily become apparent upon reading the following specification taken in conjunction with the drawings, in which:

Figure 1 is a side elevational view, partly in section, of an improved circuit interrupter embodying my invention and shown in the closed circuit position;

2

Fig. 2 is an enlarged vertical sectional view through the left-hand arc-extinguishing unit of Fig. 1, the contact structure being shown in the closed circuit position;

5 Fig. 3 is a view taken at right angles to that of Fig. 2 with the contact structure shown in the partially open circuit position, and

Fig. 4 is an enlarged fragmentary view taken substantially along the line IV—IV of Fig. 3.

Referring to the drawings, and more particularly, to Fig. 1 thereof, the reference numeral 1 designates a tank filled to the level 2 with a suitable arc-extinguishing fluid 3, in this instance circuit breaker oil. Depending from the 15 cover 4 of the tank 1 are a pair of terminal bushings 5 which support at their lower ends arc-extinguishing units, generally designated by the reference character 6.

The arc-extinguishing units 6 are electrically 20 interconnected in the closed circuit position, as shown in Fig. 1, by a bridging member 7 reciprocally operated in a vertical direction by an insulating lift rod 8. The lift rod 8 may be actuated in a vertical direction by suitable mechanism, 25 not shown, which is responsive to either manual operation or to the existence of excessive current conditions in the protected circuit.

Referring to Fig. 2, which more clearly shows the internal construction of the arc-extinguishing units 6, it will be noted that a conducting contact foot 9 is threadedly secured and clamped to the lower end of the terminal stud, not shown, which extends interiorly through the terminal bushing 5. Integrally formed with the contact 30 foot 9 is the top metallic plate 10 of the unit 6. The plate 10 in conjunction with insulating tie rods, not shown, fixedly supports in place a plurality of insulating plates, more fully described hereinafter and defining a relatively vented interrupting chamber, generally designated by the reference numeral 11. A stationary contact 13 cooperates with a movable contact 14 to establish an interrupting arc 15 within the interrupting chamber 11, as more clearly shown in 35 Fig. 3. Rigidly secured to the lower end of the movable contact 14 is an insulating rod 16, the lower end of which is fixedly secured to another movable contact member 17 which makes engagement in the closed circuit position, as shown in Fig. 2, with relatively stationary pressure-generating contacts 18.

The stationary contacts 18 are electrically connected by a vertical spider construction 19 with relatively stationary contacts 20, the latter bearing against the external surface of the movable

contact 14 during the downward opening movement thereof.

The electrical connection between the stationary contacts 18, 20 may be effected by strap connectors 21, the latter being brazed to the outer surfaces of the contacts 18, 20. Preferably, the contacts 18, 20 are pivotally mounted by pins 22 and biased inwardly toward the movable contact structure by torsion springs 23.

The movable pressure-generating contact member 17 separates from the stationary pressure-generating contacts 18 to establish a pressure-generating arc 26 within a relatively confined pressure-generating chamber, generally designated by the reference numeral 27. It will be noted that there is provided a pair of vertically extending passages 28 interconnecting the pressure-generating chamber 27 with the interrupting chamber 11. Thus, liquid under pressure from the pressure-generating chamber 27 may flow upwardly within the passages 28, as indicated by the arrows 29, into the interrupting chamber 11 to effect extinction of the interrupting arc 15 draw therein.

Suitable insulating plate structure is provided defining the interrupting chamber 11 which very effectively directs liquid into intimate engagement with the interrupting arc 15. This insulating plate structure follows the teachings set forth in United States patent application filed December 22, 1945, Serial No. 636,940, now Patent No. 2,467,760, April 19, 1949, by Leon R. Ludwig, Benjamin P. Baker, and Winthrop M. Leeds, and assigned to the assignee of the instant application. Preferably, this plate structure consists of fibre insulating plates of three different types. The first type, designated by the reference character 31, has portions removed therefrom to define inlet passages 32, more clearly shown in Fig. 2. Adjacent each inlet insulating plate 31 is an insulating orifice plate 33 having an orifice 34 provided therein through which passes the movable contact member 14 during its opening motion.

On the other side of the orifice insulating plate 33 from the inlet plate 31 is a vent plate, generally designated by the reference numeral 35. Preferably, the vent plate 35 is composite and consists of two identical halves 36 spaced laterally apart to provide a pair of opposed outwardly extending vent passages 37, more clearly shown in Fig. 3.

From the foregoing description, it will be apparent that the oil passes inwardly toward the interrupting arc 15 through the opposed inlet passages 32, thence through the orifices 34 provided by the orifice plates 33 to exhaust outwardly away from the interrupting arc 15 out of the unit 6 through the opposed vent passages 37. Extinction of the interrupting arc 15 soon follows and the circuit is interrupted.

It will be noted that the lower end of the movable contact member 17 makes electrical engagement with contact clips 38 and passes downwardly into an operating cylinder 39. The operating cylinder 39 is threaded connected at 40 to a cup-shaped metallic casting 41. The lower end of the operating cylinder 39 is closed by an apertured closure cap 42 threadedly secured, as at 43, to the lower end of the operating cylinder 39. Apertures 44 are provided adjacent the lower end of the operating cylinder 39 so that the region below the operating piston 45 freely communicates with the region 46 which is substantially at atmospheric pressure. The operating piston 45

has a lost-motion connection with the lower end 47 of the movable contact member 17. The lower end 47 of the movable contact member 17 has an enlarged metallic cylindrical member 47a rigidly secured thereto having diagonal cuts 48 formed therein. The cuts 48 cooperate with an inwardly extending flange portion 49 of the operating piston 45 to provide a valve means, generally designated by the reference numeral 50 which is closed during the downward opening motion of the operating piston 45 and movable contact member 17. The valve means 50 closes during the opening operation by virtue of the fact that the flange portion 49 covers the tops of the cuts or recesses 48. During closing the valve means 50 is open as later described.

A compression spring 52 is provided within the lower end of the operating cylinder 39, having its lower end seated upon the closure cap 42 and having its upper end bearing against an inwardly extending flange portion 53 of the operating piston 45. Thus, during the closing upward motion of the movable contact member 17, the spring 52 first raises the operating piston 45 to open the valve means 50 and subsequently after the lost-motion is taken up, strikes the cylindrical member 47a to cause thereby upward closing motion of the contact member 17, the valve means 50 being open during the entire closing operation since liquid can by pass the member 47a through the recesses 48.

My improved hydraulically operated mechanism 54 also includes a pumping piston 55 having an inwardly extending portion 56 which bears against the outer surface of the operating cylinder 39 being guided thereby. A battery of compression springs 57 is provided to bias the pumping piston 55 downwardly in the circuit opening direction to thereby compress liquid within the region 58. This liquid under pressure within the region 58 may pass through apertures 59 provided in the operating cylinder 39 to act downwardly upon the operating piston 45 in the manner previously described.

The pumping piston 55 has a depending cylindrical portion 60 which makes threaded engagement, as at 61, with an insulating tube 62, the lower end of which makes threaded engagement with a metallic bumper 63. The bumper 63 is preferably threaded, as at 64, adjacent the lower end of the insulating tube 62.

The bridging member 7 is composite, having an upper conducting portion 65 and a lower insulating portion 66. The portion 65 has an upwardly extending piece 67 which passes between a pair of jaw-type stationary disconnect fingers 68, biased toward each other by any suitable means, not shown. The disconnect fingers 68 are electrically connected by a connector 69 to the lower metallic plate 70 of the unit 6.

I have provided a cylindrically-shaped follower member 71 which has an inwardly extending flange portion 72 at its upper end. The upper edge 73 of the pumping piston 55 picks up the follower member 71 during the closing stroke against the downward biasing action exerted by a compression spring 74. The upper end of the compression spring 74 bears against the metallic casting 41, and the lower end of the compression spring 74 bears against a radially outwardly extending flange portion 75 of the follower member 71.

To facilitate low current interruption when the pressure generated within the pressure-generating chamber 27 by the pressure-generating arc

26 is relatively low, I have provided a separate independently movable pumping piston 76 which is picked up during the closing stroke by a shoulder portion 77 of the pumping piston 55. A relatively light compression spring 78 retracts the pumping piston 76 in the closed position, as shown in Fig. 2, forcing the upper end 79 thereof against stops 80 integrally formed with the casting 41.

Consequently, during the opening stroke there is a time-delay before the follower member 74 picks up the pumping piston 76 to force it downwardly by the action of the compression spring 74. The reason for the delayed action of the pumping piston 76 during low current interruption is set forth and claimed in United States patent application filed December 15, 1943, Serial No. 514,366, now abandoned, and continued in patent application Serial No. 6,436, filed February 5, 1948, by Winthrop M. Leeds, Robert E. Friedrich, and Francis J. Fry and assigned to the assignee of the instant application.

The downward opening movement of the pumping piston 76 is effective to force oil outwardly through apertures 81 provided in the casting 41 and upwardly as indicated by the arrows 82 through a separate passage means, in this instance consisting of two vertically extending passages 83.

By the provision of the passages 83, separate from the passages 28, there is no possibility of fluid within the passages 28 coming from the pressure-generating arc 26 contaminating the fluid within the vertical passages 83 moving upwardly from the auxiliary pumping piston 76. Thus, clean oil is provided by action of the pumping piston 76.

I have provided venting means 84, 85 at opposite ends of the unit 6 to provide a chimney-like venting arrangement, which venting means is hydraulically actuated at the extreme end of the opening operation. This results since I have provided a cylinder 86 secured, as by welding at 87, to the lower plate 79 of the unit 6. The cylinder 86 has apertures 88 provided therein so that during the initial downward opening motion of the pumping piston 55 liquid will not be compressed within the region 89. It is only near the end of the opening operation, after interruption of the arcs has been completed, that the downward opening movement of the pumping piston 55 is effective to compress oil within the region 89 and place the oil within the insulating tubes 90 under pressure. At this time the oil under pressure within the tubes 90 forces the pistons 91 associated with the venting means 84, 85 to open the valves 92 associated with the venting means 84, 85. Thus, at the extreme end of the opening operation contaminated fluid is permitted to freely flow out of the unit 6 by the simultaneous opening of the venting means 84, 85 at opposite ends of the unit 6.

In similar manner venting means 93 is provided at the lower end of the pressure-generating chamber 27, as shown in Fig. 3. This permits the pressure-generating chamber 27 to be freely vented at the extreme end of the opening operation. The pistons 91 associated with the venting means 93 are actuated by oil under pressure within tubes 94 which communicate with the region 89. Thus, all six of the pistons 91 are simultaneously actuated by the final downward opening travel of the pumping piston 55.

The operation of my improved interrupter will now be explained. In the closed circuit position

of the interrupter, as shown in Fig. 2, the electrical circuit therethrough includes conducting contact foot 9, conducting plate 10, shunt 95, stationary contact 13, movable contact 14, 5 stationary contacts 20, strap connectors 21, stationary contacts 16, movable contact member 17, contact clips 38, casting 41, lower plate 79, connectors 69, stationary disconnect fingers 68, 10 upstanding conducting piece 67 of the bridging member 7 and through the right-hand arc-extinguishing unit 6 in like manner to the other terminal of the interrupter.

When it is desired to open the electrical circuit passing through the interrupter, suitable mechanism, not shown, which is responsive to either manual operation or to the existence of excessive current conditions in the circuit, causes downward opening motion of the lift rod 8. The downward movement of the insulating lift rod 8 causes 20 corresponding downward opening movement of the composite bridging member 7.

The downward movement of the bridging member 7 permits the battery of compression springs 57 to force the pumping piston 55 downwardly 25 to compress oil within the region 58. This oil under pressure within the region 58 passes through the apertures 59 provided in the operating cylinder 39. This oil then acts upon the top surface of the operating piston 45 to cause it to move downwardly against the biasing action exerted by the compression spring 52. After the lost-motion between the operating piston 45 and the movable contact member 17 is taken up, the valve means 50 is closed and the downward movement of the operating piston 45 carries the movable contact 17 downwardly with it. Since the insulating portion 16 interconnects the contacts 14, 17, the pressure-generating arc 26 and the interrupting arc 15 will be substantially simultaneously established respectively within the pressure-generating chamber 27 and the interrupting chamber 11.

Oil under pressure from the pressure-generating arc 26 flows upwardly during high current interruption through the passages 28 to effect extinction of the interrupting arc 15 within the interrupting chamber 11 in a manner as previously described. During this high current interruption the auxiliary piston 76 is not effective and is merely stalled by the high pressure existing within the unit. One or more tubes 24 provide substantially atmospheric pressure in the region 25 in back of the pistons 55, 76 so that the biasing action exerted by spring 74 is overcome by the high pressure existing within the unit. It is only during low current interruption when the pressure within the pressure-generating chamber 27 is low that the auxiliary pumping piston 76 is effective to force oil upwardly through the passages 83 and into the interrupting chamber 11 to effect the extinction of the interrupting arc 15 established therein.

It will be noted that the areas of the pumping piston 55 and the operating piston 45 are such as to cause considerable travel of the contact structure for a much shorter travel of the pumping piston 55. This gives high speed opening essential for three cycle performance. It will also be noted that the path between the two pistons 55, 45 is short to reduce to a minimum hydraulic friction losses.

The pumping piston 55 continues to move downwardly under the action of the compression springs 57 as permitted by downward motion of 75 the insulating portion 68 of the bridging member

1. Finally, following interruption of the arcs, the conducting piece 67, or the movable disconnect contact, separates from the stationary disconnect fingers 68 to insert two isolating gaps in the circuit, as more clearly shown by the dotted lines 96 of Fig. 1.

It will therefore be apparent that the circuit is broken within the unit 6 and not at the disconnect contacts 67, 68, the latter separating only following circuit interruption. It will be observed that following interrupting of the arcs 15, 23 the pumping piston 55 establishes oil pressure within the regions 89 to effect opening of the venting means 84, 85 at opposite ends of the unit 6 to thereby permit contaminated fluid to freely flow out of the unit 6 by the chimney-like vent passages formed. Also as shown in Fig. 3, the venting means 93 will be opened to permit venting of the pressure-generating chamber 27.

Finally, the downward movement of the pumping piston 55 is halted by its striking the portion 97, and the compression spring 52 at this time effects reclosure of the contact structure. In other words, the compression spring 52 first forces the operating piston 45 upwardly to first open the valve means 50 permitting leakage of oil around the lower end 47 of the movable contact member 17.

After the lost-motion is taken up and the valve means 50 is open, the operating piston 45 picks up the movable contact member 17, forcing the latter upwardly to thereby effect re-engagement of the contacts 17, 18, 14, 13. Hence the electrical circuit is completed through the interrupter in the fully open circuit position thereof, the isolating gaps withstanding the impressed voltage.

During the interruption of low currents, as previously mentioned, the downward movement of the follower member 11, as caused by the biasing action of the compression spring 74, picks up the auxiliary piston 76 to force fluid up through the passages 83 and toward the interrupting arc 15.

A flap valve 98 is provided which closes the region 58 during the opening operation and permits oil to enter the region 58 through holes 99 during the closing stroke.

During the closing operation of the interrupter, suitable means causes upward closing motion of the lift rod 8. This raises the bridging member 7 and first causes engagement between the bumper 63 and the insulation portion 66 of bridging member 7. Thus, even before the disconnect contacts 67, 68 are engaged, the bumper 63 has been moved upwardly a considerable distance to thereby effect charging of the pumping piston 55. The reason for this is that if excessive current conditions still exist in the circuit during the closing operation and prestriking occurs between contacts 67, 68 to thereby reverse the motion of the operating mechanism, the pumping piston 55 will have been sufficiently charged at this time of reversal to effect opening of the contact structure in the manner previously described. In other words, if the pumping piston 55 were not partly charged by the time the contacts 67, 68 were sufficiently close together to be conductively bridged by prestriking, the pumping piston 55 would be ineffective to open the contact structure and the interrupter would fail. By partly charging the pumping piston 55 before there is a possibility of flashover between the disconnect contacts 67, 68, assurance is had that the breaker will operate in the nor-

5 mal manner should reversal of the mechanism take place at an intermediate point in the closing operation.

From the foregoing, it will be apparent that during the closing operation the actuating member 66 causes upward charging movement of the pumping piston 55 to thereby cause opening of the flap valve 98 to draw oil through the apertures 99 into the region 58. Also the shoulder portion 71 of pumping piston 55 picks up the auxiliary piston 76. Further, the upper edge 73 of pumping piston 55 picks up the follower member 11 and effects the charging motion thereof.

10 During the initial downward movement of the pumping piston 55, the compression spring 78 maintains the auxiliary pumping piston 76 against the stops 80 so that there is a predetermined time interval before the piston 76 is effective to pump oil.

15 From the foregoing, it will be apparent that my improved interrupter is particularly applicable for high speed reclosing operations due to the provision of the venting means 84, 85 and 93. Thus, 20 the gases which tend to contaminate the oil within the unit 6 are rapidly expelled therefrom following extinction of the arcs. To check the contact structure during installation of the interrupter, it is necessary only to thread a long stud, 25 not shown, into the tapped hole 100 and move the two contacts 14, 17 and the insulating portion 16 vertically. The interrupter is easily installed requiring only that the bridging member 7 be sufficiently aligned to cause the conducting portion 30 35 40 45 50 55 60 65 70 75 80 85 90 95 100 105 110 115 120 125 pump piston surrounding the operating cylinder and having the region of compression immediately adjacent the external surface of the operating cylinder, and apertures through the operating cylinder so that the travel of fluid between the two pistons will be short to minimize hydraulic friction losses.

2. A circuit interrupter having contact means operable to establish an arc including a movable contact, an operating piston for actuating the movable contact, an operating cylinder within which the operating piston moves, a movable pump piston surrounding the operating cylinder and having the region of compression immediately adjacent the external surface of the operating cylinder, apertures through the operating cylinder so that the travel of fluid between the two pistons will be short to minimize hydraulic friction losses, means biasing the movable contact toward its closed position, and valve means associated with the operating piston to permit fluid leakage around the operating piston during the closing movement of the movable contact.

3. A circuit interrupter including a pair of arc-extinguishing units, each unit having contact means operable to establish an arc including a movable contact, an operating piston for actuating the movable contact, an operating cylinder within which the operating piston moves, a movable pump piston surrounding the operating cylinder and having the region of compression immediately adjacent the external surface of the operating cylinder, apertures through the operating cylinder so that the travel of fluid between the two pistons will be short to minimize hydraulic friction losses, and a movable bridging member electrically connecting the two units in series in the closed circuit position and charging the two movable pump pistons associated with the two units.

4. A liquid break arc-extinguishing unit having contact means including a movable contact member separable to establish an arc, a hydraulic operating mechanism for the movable contact member including an operating piston operatively connected with the movable contact member, an operating cylinder within which the operating piston moves, a movable pumping piston for forcing liquid into the operating cylinder to effect thereby opening motion of the operating piston and movable contact member, means biasing the pumping piston in a direction to separate the contact means, an actuating member to charge the pumping piston during the closing operation of the unit against said biasing means, and another pumping piston operatively related to the pumping piston to assist in low current interruption.

5. A liquid break arc-extinguishing unit having contact means including a movable contact member separable to establish an arc, a hydraulic operating mechanism for the movable contact member including an operating piston operatively connected with the movable contact member, an operating cylinder within which the operating piston moves, a movable pumping piston for forcing liquid into the operating cylinder to effect thereby opening motion of the operating piston and movable contact member, means biasing the pumping piston in a direction to separate the contact means, an actuating member to charge the pumping piston during the closing operation of the unit against said biasing means, a follower member, means biasing the follower member in said direction, and a delayed acting piston picked up after a predetermined travel of the follower member to assist in low current interruption.

6. A liquid break arc-extinguishing unit having contact means including a movable contact member separable to establish an arc, a hydraulic operating mechanism for the movable contact member including an operating piston operatively connected with the movable contact member, an operating cylinder within which the operating piston moves, a movable pumping piston for forcing liquid into the operating cylinder to effect thereby opening motion of the operating piston and movable contact member, means biasing the pumping piston in a direction to separate the contact means, an actuating member to charge the pumping piston during the closing operation of the unit against said biasing means, venting means for the arc-extinguishing unit, and means whereby the pumping piston opens the venting means near the end of its opening motion in said direction to vent the unit.
